RESILIENT SAFETY MAT

William J. Lutey, Seattle, Wash.

Application July 10, 1937, Serial No. 152,966

5 Claims. (CL. 20—78)

This invention relates to resilient safety mats in general, and particularly to mats and step treads having bases of solid material adapted to hold strips of resilient non-slip material in a novel manner.

An embodiment of the invention comprises a base of hard material, such as metal, that provides a plurality of slots adapted to receive strips of soft resilient material, such as may be cut from rubber tire casings, that are wound about the portions of the base between slots to form a plurality of elliptically spiralled coils.

An object of the invention is to provide an article of the kind described, that has the resilient material so arranged that it will increase greatly its effective resiliency and non-slip features, yet permit its replacement easily and quickly when worn.

Another object is to provide an article of the kind described, that lends itself readily to different color schemes by changing only the color of the finish applied to the surface of the base without changing the neutral color of the resilient material.

A further object is to provide an article of the kind described, that may be made in comparatively small units, which in turn may be linked together to provide mats of various larger sizes, for convenience in moving, and for immersing in an antiseptic solution, thus greatly increasing its sanitary features.

Other objects and advantages will be apparent to those skilled in the art from the following detailed description of a preferred form of the invention, which consists of certain parts and combination of parts, hereinafter described, illustrated in the accompanying drawing, and embraced in the appended claims.

In the drawing:

40 Figure 1 is a plan view of one unit of my invention, with one row of the elliptically spiralled coils omitted to better show the slots.

Fig. 2 is a transverse section through the unit taken on broken line 2—2 of Fig. 1, to a smaller scale, and with all coils in place.

45 Fig. 3 is a plan view, to a still smaller scale, of two units fastened together by a plurality of links to form a mat of larger size.

Fig. 4 is a fragmentary section through a portion of one of the coils, taken on broken line 4—4 of Fig. 1, to a larger scale.

50 Fig. 5 is a fragmentary section through the linked edge portions of two units, taken on broken line 5—5 of Fig. 3 to a larger scale.

55 Like reference numerals are used to indicate

like parts throughout the drawing, wherein 6 illustrates a preferred form of base that may be of any suitable material. If made of sheet metal, slot apertures 1a, 1b, 8a and 8b, holes 9, holes 10 and notches 11, all may be punched in one 5 operation of a suitable punch and die press, after which bevel edges 6e may be formed in another press with a forming die.

It will be noted in Fig. 1, that the slots are arranged in double rows, with a pair of shorter 10 slots 1a and 1b at the opposite ends of adjacent double rows, thus placing the intervals between slot pairs opposite the mid-point of the slot pairs of the adjoining rows. It will be noted also that the ends of slots 1a and 8a are displaced slightly 15 with reference to the corresponding ends of slots 1b and 8b, respectively, for the reason about to be explained.

Strips of resilient material 12, preferably made from the multiple layer rubberized fabric of the 20 casings of old automotive vehicle tires, are provided near their ends with slots 12s in preparation for use to form the elliptical spiral coils hereinbefore mentioned.

Starting at the center, one notched end of a 25 prepared strip is passed through slot 8a and the other end through slot 8b of the base. The ends are then brought together and the strip pulled through as far as possible to equalize the lengths extending from the two slots. An elliptical spiral 30 coil then may be wound quickly and easily around the intervening portion of the base by passing first one end successively through the pair of slots mentioned until the notched end comes opposite the base at the left end, say of slot 8a. 35 The wound portion of the coil is then pushed firmly toward that end, thus holding the end of the strip securely in position as may be seen in Fig. 4.

The other end of the strip, likewise, then may 40 be passed successively through the pair of slots until the notch at the end is seen to be ready to engage the base at the right end of slot 8b, whereupon the coil is compressed toward the other end of the slot until the notched end can 45 be entered, then the coil is released.

In this manner the resiliency of the coil continuously holds the notched ends of the strip in engagement with the base at the ends of slots 8a and 8b, respectively, the length of strip and distance between notches having been predetermined to make possible this simple procedure and the resulting construction. From the foregoing it will be understood, that both ends of each coil strip are held in position by the engagement of 50 55

- the aforesaid notches with the base at the opposite ends of one or the other of the slots in which the coil is wound, and this applies also to the shorter coils 13 wound in slots 1a and 1b. By reversing the procedure, obviously the coils may be removed, thus enabling worn coils to be easily and quickly replaced by new ones at little expense. Because of the diagonal position taken by the turns of the coiled strip material from slot to slot, it will be seen by referring to Fig. 1, that the construction of the mat is improved by offsetting the corresponding ends of the pairs of slots sufficiently to facilitate the engagement of the notched ends of the strips with the base, without 15 distorting the natural lay of said coiled strip material.
- Referring now to Fig. 2, with the coils wound in place as described, it will be seen that the lower sides of each turn of the coils will rest upon the supporting surface. The elliptical shape of the coil turns provides a large percentage of bearing and wearing surfaces, and imparts an outstandingly pleasant resiliency, that is due in part to the material used but principally to my improved arrangement, which provides a cushioning effect in the coils both above and below the base, and in the deck of the base itself. The open construction of the elliptical spiral coils also provides excellent ventilation.
- 30 The multiplicity of elliptical turns forming the coils present a large number of corner edges, which have been found to be particularly effective in preventing the feet from slipping on the mat, and likewise in preventing the mat from slipping on its supporting surface. In addition to this, as weight is placed on a given section of the mat, the material in the coils sinks more or less below the surface level of the surrounding coils, thus greatly increasing the non-slip 35 characteristics of the mat.
- By standardizing the size of the unit the cost of production can be minimized. When it is necessary to cover larger areas, two or more units may be joined together, either at their ends 40 or at their sides, or both, by means of links 14, which pass through holes 10 and slots 11 in base edges 62, as shown in Figs. 3 and 5.
- There is also another advantage in this construction.
- 50 It will be apparent that a mat comprising a plurality of linked units may be quickly folded, washed easily and immersed, if desired, in an antiseptic solution, thus providing for greatly increased sanitation in and about kitchens, hospitals and other places where this may be an important factor. By means of a plurality of linked units, and the cutting of some of the outer units, it is possible to adapt my mat to a great variety of places having odd and unusual shapes.
- 60 The color of the rubberized fabric is a neutral

shade of grey. By providing a suitable mat for the base, it will be seen that my mat may be made to match or harmonize with any desired color scheme.

Holes 9 may be provided for screws or other means not shown, for fixing the mat in place, if desired.

Although I have confined my drawing and description to a mat, it will be understood that by changing the proportions, a step tread may be 10 formed that has all of the desirable characteristics of the mat.

It will also be apparent to those skilled in the art, that the essential coacting elements may be constructed in various other equivalent forms 15 and from other materials without departing from the purpose and intent of the invention within the scope of the appended claims.

Having described my invention, what I claim as new and desire to protect by Letters Patent is: 20

1. A safety mat comprising a base having a plurality of slot apertures therein, and a plurality of spiral coils of resilient material wound upon the portions of said base between said apertures.

2. A safety mat comprising a base having a plurality of slot apertures therein, a plurality of elliptical spiral coils of resilient material wound upon the portions of said base between said apertures, and means for securing the ends of said 30 coils to prevent the coils from unwinding.

3. A safety mat comprising a base having a plurality of slot apertures arranged in a plurality of double rows, with a pair of shorter slot apertures at the opposite ends of adjacent said double rows, a plurality of elliptical spiral coils of resilient material wound upon the portions of said base between the apertures of said double rows, and means for securing the ends of said coils to said base.

4. A safety mat comprising a base providing a plurality of parallel slot apertures arranged in a plurality of double rows with a pair of shorter slot apertures at the opposite ends of adjacent said double rows, a plurality of elliptical spiral 45 coils of resilient material wound upon the portions of said base between the apertures of said double rows, and notch means in the ends of said strips for fastening said ends to said base.

5. A plurality of safety mat sections, each comprising a base providing a plurality of slot apertures and a plurality of holes near its edges, a plurality of elliptical spiral coils of resilient material wound upon the portions of said base between the apertures of said double rows, 55 fastening means for securing said ends to said base, and link means passing through said holes for joining said mat sections together.

WILLIAM J. LUTEY. 60
